UNITED STATES PATENT OFFICE.

JULIUS MOELLER, OF MOSCOW, RUSSIA.

CARRYING DEVICE.

SPECIFICATION forming part of Letters Patent No. 707,610, dated August 26, 1902.

Application filed August 22, 1901. Serial No. 72,931. (No model.)

To all whom it may concern:

Be it known that I, JULIUS MOELLER, a subject of the Emperor of Russia, residing at Moscow, in the Empire of Russia, have invented 5 certain new and useful Improvements in Carrying Devices, of which the following is a specification.

My invention relates to an improved carrying device adapted to be attached to the 10 body of a person; and it consists of a belt provided with shoulder-pieces advantageously arranged to sit crosswise over the back of the wearer and formed with loops on the belt for holding the object which it is necessary to 15 carry, it being chiefly intended for use in carrying stretchers.

The object of my invention is to provide an improved device whereby an even distribution 20 of the weight upon the shoulders, back, and hips of the wearer is obtained without hindering the latter in the free use of his hands, so as to relieve the shoulders and hips. I attain this object by the device illustrated in 25 the accompanying drawings, in which—

Figure 1 is a perspective front view of the carrying device; Fig. 2, a perspective back view thereof, and Fig. 3 a perspective side view of a special modification of the device.

Similar letters refer to similar parts throughout the several views.

The improved carrier-strap consists of a belt *a*, provided with a buckle *b* and two shoulder-straps *c*, rigidly attached by their rear ends to the said belt at *d*, while their 35 front ends are provided with buckles *e* for securing them adjustably to the front part of the belt *a*. At the fore part of the belt *a* and advantageously at both sides of the shoulder-strap attachments *f* are fixed the ends of loop- 40 straps for holding the stretcher, and such loop-straps may be formed of two portions *i* and *h*, adjustably secured together by buckles *g*. In all the views of the drawings said loops are shown as "not closed"—*i. e.*, the portions *i* 45 are not attached to the buckle *g*. Under normal conditions, however—that is to say, when the device is being used for carrying a stretcher—said portions *i* and *h* must be attached to each other by means of the buckle *g*, so as to form a real loop for the ends of the 50 poles of the stretcher to be laid in.

According to the slightly-modified form shown in Fig. 3 the ends of the shoulder-straps *c* are not fixed to the belt at *d*, as in Figs. 1 and 2, and are prolonged downward 55 to form the loop-straps *h* for attachment to the front ends *i*, fixed at the front of the belt *a*.

The advantages of my improved device as compared with other similar means consist mainly in the fact that the burden, independent 60 of any aid from the hands, is well divided over the shoulders, back, and hips of the bearer and without inconvenience to the chest, while, moreover, the weight which is borne by the shoulders and back in proportion 65 can be regulated as may be desired. By tightening the belt *a* as far as can be—for example, very tight—around the body of the bearer the largest portion of the weight will be on the hips or carried by the hands of the bearer. 70 If, however, the belt be loosened to some extent, the weight will partly be borne by the shoulders and back of the bearer, and by adjusting the belt very loosely around the body 75 the weight will all hang on the shoulders and body of the bearer, if no account is taken of the support afforded by the hands.

What I claim as my invention, and desire to secure by Letters Patent, is—

In combination, a belt, shoulder-straps 80 crossing at the back and secured to the back of said belt at their rear ends, adjustable connections between the front ends of said straps and the front portion of said belt, an adjustable connection for the ends of said belt and 85 loops connected to said belt and comprising a pair of straps *h* secured one to each side of the belt where it rests on the hips and a second pair of straps *i* secured to the belt near the adjoining ends, said straps *h* and *i* having means 90 for detachably connecting their free ends, substantially as described.

In testimony whereof I have signed my name to this specification in the presence of two subscribing witnesses.

JULIUS MOELLER.
